UNITED STATES PATENT OFFICE.

WILLIAM WHITE, OF PASSAIC, NEW JERSEY, ASSIGNOR TO CLARENCE WHITMAN & CO., OF NEW YORK, N. Y.

DESIGN FOR A BED-SPREAD.

SPECIFICATION forming part of Design No. 24,124, dated March 19, 1895.

Application filed January 30, 1895. Serial No. 536,718. Term of patent 3½ years.

To all whom it may concern:

Be it known that I, WILLIAM WHITE, a subject of the Queen of Great Britain, residing in Passaic, Passaic county, and State of New Jersey, have invented and produced a new and original Design for Bed-Spreads, of which the following is a specification.

The leading feature of my design consists of a bed-spread of essentially the configuration and representation shown in the accompanying drawing which exhibits a quarter section of a bed-spread partly in full detail and partly in outline.

In the drawing, *a a a a* are longitudinal bands, and *b b b* are longitudinal bands substantially parallel thereto.

c c c c are transverse bands running at substantially right angles to the beforementioned bands. These bands with lattice-work squares *d d d d* constitute the field of the bed-spread, which field is bordered by a band *e* and a band *f*, the entire spread being bordered by a band consisting of representations of juxtaposed parallelopipeds *g* and checker-board effects *h*.

What I claim is—

The design for a bed-spread, as herein shown and described.

WILLIAM WHITE.
